DESIGN FOR WALL-PAPER.

SPECIFICATION forming part of Design No. 21,938, dated November 1, 1892.

Application filed October 3, 1892. Serial No. 447,723. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying drawing, forming part thereof.

10 The leading feature of this design consists of two small semicircular sprays of flowers and leaves arranged in the form of an open or disconnected wreath, as represented in the accompanying drawing. The stems of the two 15 sprays are united by a ribbon wound loosely

around the stems, which also forms a part of said design.

The design is arranged at regular distances apart over the surface of the paper and is printed in any desired color upon tinted paper of any desired color.

What I claim is—

The design for wall-paper herein shown and described.

Witness my hand this 30th day of September, 1892.

CHARLES BOOZE.
